UNITED STATES PATENT OFFICE.

CHARLES E. WHITE, OF MOLINE, ILLINOIS, ASSIGNOR TO THE DEERE & MANSUR COMPANY, OF SAME PLACE.

CORN-PLANTER.

SPECIFICATION forming part of Letters Patent No. 379,838, dated March 20, 1888.

Application filed January 3, 1888. Serial No. 259,573. (No model.)

To all whom it may concern:

Be it known that I, CHARLES E. WHITE, a citizen of the United States, residing at Moline, in the county of Rock Island and State of Illinois, have invented certain new and useful Improvements in Corn-Planters, of which the following is a specification.

This invention relates to that class of corn-planters in which a main frame mounted on supporting-wheels is hinged to a forward frame provided with runners or furrow-openers, and in which lever mechanism fulcrumed to the rear main frame is used to raise and lower and to adjust and fix the height of the forward frame relatively to the rear frame.

A leading object of my invention is to provide a hand-lever and a foot-lever, both pivoted to the rear frame of the planter, and the foot-lever hinged at its forward end to the forward frame and its rearwardly-extended end connected with the rearwardly-extended end of the hand-lever by a link-rod and spring in such manner that when the hand-lever is locked in a fixed position with reference to the other parts of the planter, and in such a position as to hold the runners in the ground, they (the runners and forward frame) will be held or depressed by a yielding spring-pressure, the force of which spring-pressure is controlled or regulated by adjusting the hand-lever, and is of such degree as to cause the runners to cut into hard soil and through ordinary obstructions, while it permits them to rise or yield upwardly to pass over still harder obstructions, which it is not practicable or desirable to cut through, and, further, to cause the runners to conform to inequalities of the ground, whether in hardness and mellow ness or in irregularities of the surface, so as to deposit the seed in such ground at substantially uniform depths.

A further object of my invention is to connect the hand and foot levers in such manner that the hand-lever may be used to raise and lower and depress the forward frame and to lock and hold the forward frame with a spring-pressure, and the foot-lever be used to raise and lower the forward frame while the hand-lever is in either its locked or unlocked position, and both levers be used together to raise and lower the forward frame and to lock and hold

said frame in position rigidly against downwardly-acting force and with a yielding spring-pressure, as hereinbefore stated, against upwardly-acting force.

A further object of my invention is to provide a connecting link-rod between the foot-lever and forward frame having an extended upward end with foot-plates, on which the driver may place his feet to depress the forward frame.

The various features of construction and the combinations employed by me in one method of embodying my improvements in an ordinary planter are hereinafter fully described, and are recited in the claims herewith.

The accompanying drawings illustrate the same by figures as follows: Figure 1 is a top plan of the principal parts of an ordinary corn-planter partly broken away to show my improvements which are applied thereto; Fig. 2, an elevation partly in section; Fig. 3, a perspective showing the hand and foot levers, their spring-connection with each other, the connection of the foot-lever and forward frame, the curved rack-bar, and parts of the seat-bar and planter-axle. Fig. 4 is a sectional elevation in the line 4 4 in Fig. 1.

The rear frame, A, of the ordinary planter (shown in the drawings) consists of bars *a*, axle *a'*, and bar *a''*, supported on wheels B and supporting a seat, C, on a bar, *c'*, and brace *c''*. The bars *a* are hinged at their forward ends to the transverse bar *d* of the forward frame, D, which forward frame further consists of a forward transverse bar, *d'*, and bars *d''*, which have rearwardly-extended ends *d'''*. The runners or furrow-openers *d''* are secured to the frame D. This construction of planter is an ordinary type thereof, and the hereinafter description of one method of applying my improvements thereto will enable any one skilled in the art to apply them to any planter to which they are applicable.

E is a hand-lever pivoted at *e* to a bracket projecting from the axle-bar *a'*. This lever E has a handle part, *e'*, and a rearwardly-extending part, *e''*, which parts together constitute a bell-crank lever. The lever E is also provided with an ordinary locking dog or pawl, *e'''*, which engages with the teeth of a

curved rack-bar or segment-bar, e^4 , which rack-bar is also fixed to the axle-bar a' . The pawl e^3 is operated by an ordinary thumb-lever, e^5 . G is a foot-lever fulcrumed or pivoted on the same pivot as the lever E . It will be evident, however, that it may be pivoted on a separate pivot; but said pivot should be coincident with or substantially in line with the pivot of the lever E . The lever E may also be pivoted to any suitable part of or projection from the rear or main frame, A , and the rack-bar e^4 may be fixed to any similar projection from or part of said frame. The forward end, g , of the lever G extends forward and has a series of holes, g' , through either of which a pivot-bolt, g^2 , passes to secure it to a link, I , hereinafter described. The rear end, g^3 , of the lever G extends rearwardly beyond the extended end e^2 of the lever E , and has foot-plates g^4 on its rear end. The rear end of the arm e^2 of lever E is bent to fit over a flattened part of the end g^3 of the lever G , and both arms e^2 g^3 have coincident holes through which a rod, h , passes. The rod h has a nut, h' , on its lower end and a nut, h^2 , on its upper end. A spiral spring, H , encircles the rod h between the nut h' and the rear end, g^3 , of lever G .

The link I is pivoted at its lower end between lugs j , which project upwardly from a plate, J , which is fixed to the rear ends and under sides of the extensions d^3 of the bars d^2 . The link I is slotted and receives the forward end, g , of the lever G in said slot, where it is held by the pivot-bolt g^2 , which can be placed in either of a series of holes, i , in the link I , to adjust the parts for deeper or shallower planting. The bolt g^2 may be adjusted in the holes g' to increase or diminish the leverage, and also for deeper or shallower planting. The link I has foot-plates i' on its upper end, on which the driver may place his feet to force the runners into the ground, when desirable to do so for any reason. It will be evident that the foot-lever G may be connected with the forward frame by any suitable hinge-connection, or, if preferred, be connected therewith, as shown and described in Letters Patent to James W. Atkinson, of March 9, 1880, No. 225,318.

At Figs. 2 and 4 the planter is shown, by full lines, adjusted for operation in planting, the hand-lever being there shown as locked in a position to hold the runners d^4 very deep in the soil.

The depth of penetration of the soil can be regulated and controlled by adjusting and locking the hand-lever at various positions on the rack-bar e^4 ; and, as shown by dotted lines at Fig. 4, while adjusted at either of said positions, the runner can rise to pass over obstructions, and in so doing will move the foot-lever G and compress the spring H , which resists said movement with a yielding force. When the runner and forward frame are raised by an obstruction or passing over ground with uneven surface, as last described, the hand-lever will remain fixed in its locked position and will prevent the run-

ner and forward frame from sinking any lower than as gaged by said hand-lever with an unyielding or positive force, arising from the fact of the rear end of the part e^2 of the hand-lever resting directly upon and in contact with the rear part of the foot-lever; and for the same reason, when the hand-lever is swung rearwardly to elevate the forward frame and runners, it will act positively on the foot-lever and give a positive motion to said parts. The runners and forward frame may be elevated, for turning the planter around or for other purposes, by swinging the hand-lever rearwardly, as shown by dotted lines at Fig. 2. By holding the pawl e^3 out of engagement with the rack-bar e^4 , either by hand or otherwise, the forward frame will be free to rise and fall, in the manner of an ordinary planter, without any locking lifting-lever mechanism. By removing the nut h^2 the spring H and rod h may be removed, or the spring rendered inoperative, and the runners and forward frame can then be raised and lowered by the foot-lever alone. By adjusting either nut h' or h^2 on the rod h the tension of the spring H may be adjusted to cause it to exert a greater or less depressing force on the forward frame and runners, as may be required in soil of different degrees of mellowness, or for other purposes.

What I claim as new is—

1. In a corn-planter, and in combination, substantially as described, with the front and rear frames thereof hinged to each other, a hand-lever and a foot-lever both fulcrumed on the rear frame at points in line with each other transversely of the planter, the foot-lever suitably hinged at its forward end to the forward frame and its rear part resting or located partly beneath a rear extension from the hand-lever and having a mere contact-connection therewith, whereby the hand-lever may be used to operate the foot-lever to raise and lower the forward frame and to lock it in an elevated position, or the foot-lever may be used independently of the hand-lever for raising and lowering the forward frame.

2. In a corn-planter, and in combination, substantially as described, with the front and rear frames thereof hinged to each other, a hand-lever and a foot-lever both fulcrumed on the rear frame, the rear part of the foot-lever resting or located partly beneath a rear extension from the hand-lever, whereby the hand-lever may be used to operate the foot-lever or the foot-lever be used independently of the hand-lever, and a link hinged at one end to the forward frame, at its middle portion to the forward end of the foot-lever, and having an upper end extended above said foot-lever and provided with foot-plates, for the purpose specified.

3. In a corn-planter, and in combination, substantially as described, with the front and rear frames thereof hinged to each other, a foot-lever hinged or fulcrumed on the rear frame, and a link hinged at its lower end to the front frame, at its middle portion to the

foot-lever, and having an upper end extended above its connection with the foot-lever and provided with foot-plates, for the purpose specified.

- 5 4. In a corn-planter, and in combination, substantially as described, with the front and rear frames thereof hinged to each other, a locking hand-lever and a foot-lever both fulcrumed on the rear frame, the forward end of 10 the foot-lever connected by a hinge-connection with the forward frame and its part in rear of its fulcrum resting or located partly beneath a rear extension from the hand-lever, where the two levers are yieldingly connected by a 15 spring, which forms an element in this combination and by means of which a yielding downwardly-acting force may be used on the forward frame and runners, for the purpose specified.
- 20 5. In a corn-planter, and in combination, substantially as described, with the front and rear frames thereof hinged to each other, a locking hand-lever and a foot-lever both fulcrumed on the rear frame, the forward end of 25 the foot-lever connected by a hinge-connection with the forward frame and its part in rear of its fulcrum resting or located partly beneath a rear extension from the hand-lever, where the two levers are yieldingly connected by a spring, 30 and a rod with suitable nuts or heads on its ends, which spring, rod, and nuts or heads form elements in this combination, and by means of which a yielding downwardly-acting force may be used on the forward frame and runners, for the purpose specified.
- 35 6. In a corn-planter, and in combination with the front and rear frames thereof hinged to each other, a foot-lever and a hand-lever connected by a spring, substantially as and for the purpose specified.
- 40 7. In a corn-planter, and in combination with the front and rear frames thereof hinged to each other, a foot-lever and a hand-lever connected by a spring and a rod, substantially as 45 described, and for the purpose specified.
- 50 8. In a corn-planter, and in combination with the front and rear frames thereof hinged to each other, a foot-lever and a hand lock-lever hinged to the rear frame and connected 55 with each other by a spring, H, and rod, h, with nuts or heads, substantially as and for the purpose specified.
- 60 9. In a corn-planter, and in combination with the front and rear frames thereof hinged to each other, a foot-lever and a hand lock-lever hinged to the rear frame and connected with each other by a spring, H, and a rod, h, having an adjustable nut on one or both of its ends, substantially as and for the purpose specified.
- 65 10. In a corn-planter, and in combination with the front and rear frames thereof hinged to each other, a foot-lever having foot-plates on its rear end and its forward end connected with the forward frame by a hinged link, I,

having foot-plates on its upper extended end, and a locking hand-lever connected by a rod, h, and a yielding spring, H, substantially as and for the purpose specified.

11. In a corn-planter having a front and a rear frame hinged to each other and in combination therewith a foot-lever and a hand-lever fulcrumed coincidently but independently of each other on the rear frame, and connected, the forward end of the foot-lever with 70 the forward frame and the rear ends of both levers by a rod and spring, in such manner that the hand-lever acts directly on the foot-lever when used to operate the foot-lever to raise the forward frame, and acts thereon by 75 means of the spring when used to depress the forward frame and runners, and which permits the forward frame to be raised by the foot-lever while the hand-lever is locked, substantially as and for the purpose specified. 80

12. In a corn-planter having a front and a rear frame hinged to each other and in combination therewith a foot-lever and a locking bell-crank hand-lever fulcrumed coincidently on the rear frame, the foot lever connected at 90 its forward end with the forward frame and at its rear end, by means of a yielding connection, with the hand-lever, substantially as and for the purpose specified.

13. In a corn-planter having a front and a rear frame hinged to each other and in combination therewith a bell-crank hand-lever, E, rock-bar e⁴, foot-lever G, connecting-link I, spring H, and rod h, with suitable nuts or heads, substantially as and for the purpose 100 specified.

14. In combination with the front and rear frames of a corn-planter hinged to each other, a foot-lever, G, hinged to the rear frame, and a link, I, hinged to the forward frame and 105 provided with foot-plates i' and a series of holes, i, for adjustably connecting it with the foot-lever, substantially as described.

15. In combination with the front and rear frames of a corn-planter hinged to each other, 110 a foot-lever, G, hinged to the rear frame and provided with a series of holes, g', by means of which it is adjustably connected with the link I, which is hinged to the forward frame, substantially as and for the purpose specified. 115

16. In a corn-planter having a forward and a rear frame hinged to each other, bell-crank lever E, and foot-lever G, connected by a rod, h, which passes through coincident holes in said levers, and by a spring, H, and a link 120 connecting said foot-lever with the forward frame, substantially as and for the purpose described.

In testimony whereof I affix my signature in presence of two witnesses.

CHARLES E. WHITE.
